Isaac Hooton and J. H. Cummings of Boston, Mass.

Letters Patent No. 2217. Dated Nov. 7, 1865.

Design for an Army Badge.

The Schedule referred to in the Letters Patent and making part of this same.

To all whom it may concern:

Be it known that we, Isaac Hooton and J. H. Cummings both of Boston in the County of Suffolk aforesaid of Massachusetts, have invented an ornamental Design for an Army Badge, &c. and we do hereby declare that the following, taken in connection with the drawings which accompany and form part of this Specification is a description of our invention sufficient to enable those skilled in the art to practice it.

The Design which is shown in the drawings, and which constitutes our invention is intended for an ornamental badge or pin to be worn by soldiers. It consists of the letters U. and S. unjoined as shown and surrounded and filled in with any desirable ornamentation and with the designation of the Army Corps, Division, Regiment and Company to which the soldier may belong.

Claim.

We claim the ornamental Design for an Army Badge or Pin as shown in the drawing.

In witness whereof we have hereunto set our hands this Twenty second day of September A. D. 1865.
